UNITED STATES PATENT OFFICE

170,860

CHILD'S HEAD SUPPORT FOR USE IN BATHTUBS

Evelyn Harris, Pelham Manor, N. Y.

Application June 15, 1953, Serial No. 25,494

Term of patent 7 years

(Cl. D4—3)

To all whom it may concern:

Be it known that I, Evelyn Harris, a citizen of the United States of America, residing at Pelham Manor, in the county of Westchester and State of New York, have invented a new, original, and ornamental Design for a Child's Head Support for Use in Bathtubs, of which the following is a specification, reference being had to the accompanying drawing, forming a part thereof.

Fig. 1 is a front elevational view of a child's head support for use in bathtubs, showing my new design.

Fig. 2 is a top plan view thereof.

Fig. 3 is a side view thereof.

Fig. 4 is a rear elevational view thereof.

I claim:

The ornamental design for a child's head support for use in bathtubs, substantially as shown.
EVELYN HARRIS.
